UNITED STATES PATENT OFFICE.

CHARLES DENNISTON BURNETT, OF WESTMINSTER, LONDON, ENGLAND.

CONSTRUCTION OF BUILDINGS, DWELLING HOUSES, AND SIMILAR STRUCTURES.

Application filed July 10, 1925, Serial No. 42,744, and in Great Britain May 27, 1924.

This invention relates to buildings, dwelling houses and similar structures, the object being to cheapen the construction and expedite the erection thereof.

According to the present invention a building, dwelling house or other structure is produced by manufacturing the component parts thereof in the form of co-operating standardized units or sections of large size adapted to occupy predetermined positions in the building, dwelling house or other structure, and by assembling a set of said units or sections in their correct relative positions. The sections may be composed of any suitable material such as mineralized wood mixed with cement or concrete, or from concrete, cement, sheet or corrugated metal or the like or a combination of these materials. It is preferred, however, to construct the parts from a material which can be cast, pressed or moulded and which is lighter than cement or concrete such as mineralized wood mixed with cement or concrete and with or without reinforcing material, suitable methods of producing this material being described in my co-pending patent applications Ser. Nos. 40,497, 40,498 and 50,749, as the use of this material permits large units to be manufactured which are comparatively light in proportion to their size and which, can, therefore, be conveniently handled.

When using a material which can be cast, pressed or moulded, various moulds are provided the shape or configuration of each mould corresponding to, and being adapted for the production of, one type or pattern of co-operating unit; or pellets, side plates, formers or the like may be associated with a standard moulding box; the medium which sets as a solid, is located, cast or poured therein, and the units, after the medium sets or partly sets, are removed from the moulds, and after, if desired, being subjected to subsequent or finishing treatment, they are assembled or secured together in the predetermined positions allocated to them, and for which they have been adapted, thus producing the complete house, building, structure or part thereof.

The units or sections for the production of the outer or inner walls will usually be of the same height as one of the floors of the building or dwelling house, and of a width suitable for the convenient handling, transportation and erection thereof, the requisite openings, protuberances or recesses for the

production or formation of doors, windows, fireplaces, flues, cupboards, stairs, picture rails, gutters, pipes, etc. being formed in, or constructed integral with, different units, or they may be produced by assembling two or more units each provided with co-operating parts. The floor sections, in cases where they are also constructed from standard units, may be of sufficient width to extend from one room wall or partition to the opposite wall or partition, and at the end of each floor section, connecting means, such as upstanding bosses, may be provided which fit into grooves or recesses in the wall sections, or the converse arrangement may be employed.

Each roof unit or section may be adapted to extend from the ridge to the eaves, and gutter sections may be formed at one end thereof as also a recess at the other end for accommodating other units which serve to maintain at the ridge or apex of the roof, a watertight joint between the abutting ends of the units.

The roof sections may be treated in any desired manner so as to imitate tiles or slates and the outer wall sections may also be finished off to represent stone or brickwork. To this end the moulds may be suitably shaped to give the desired effect or the sections may be treated while still in a plastic condition with the same object in view. The outer walls may also be rough cast, or the plastic material may be cast onto wooden beams located at the base of the moulds so as to give a "timber" effect.

The units or sections may be provided at their edges with grooves, recesses or protuberances, so that they interengage with one another when assembled. They may also be cemented together by a suitable medium and/or secured together by mechanical devices; for example, by means of rods which are inserted through openings so as to couple contiguous units together. The units may be painted, lined, covered or otherwise treated before transportation to the site of erection or after erection. The walls, etc., may also be attached together by providing recesses in the contiguous sections adapted to be filled up with a plastic medium such as cement, the grooves, where provided, being preferably dovetailed or undercut so as to assist in securing the units together. Any metal, wooden or other fittings required at different parts of the building may be

formed or attached to the units during or after manufacture. For example, metal window frames may be located within the moulds which are adapted to produce wall sections having window openings and the plastic material cast around the frames so that when the section has set the window frames are secured in position.

Certain units may be hollow for example, the inner walls may be formed integral with the outer walls or be adapted to be attached thereto in such manner as to leave an air space between the same. Alternatively, the outer walls may be provided with projections to which inner wall sections or layers of covering material may be secured in any desired manner thus forming the aforesaid air spaces. Sound deadening materials may be located between the inner and outer walls, partition walls, etc., and projecting metal or other strips may be provided to prevent damp or rain penetrating between the seams of abutting units, especially where corners are formed.

In order to centralize as far as possible the requisite labour required in producing the various units, the different units according to the place, purpose or function which they are adapted to fulfil when erected in their proper position in the building or structure are preferably manufactured and completed as far as possible in a central unit constructing factory and thereafter transported to the site where the house or other structure is to be erected, and, as they are of standardized design and as each unit has a definite position assigned to it in the assembly of the component parts, the mass production of the units and their erection can be carried on expeditiously and with unskilled labour. The foundations of the house or building may be constructed in any suitable manner and the building units assembled in place thereon, or located within or secured to a low foundation wall, the units, or the foundation wall, being provided if desired with metal connections embedded therein for attaching the parts together and securing the wall and other sections thereto.

Practically every part of the building or dwelling house, including walls, windows, doors, floors, roofs, party walls, partitions, stairs, flues, chimneys, gutters, etc., can thus be produced in factories and transported to the building site for assembly, so that the present method has the advantage that individual units, or the entire set of co-operating units which, when assembled, produce a structure of standardized design, can be constructed in factories situated either adjacent to, or remote from, the site where the buildings and dwelling houses are to be erected and where labour is cheap or specialized for mass production and materials accessible, the units after being wholly or

partly finished being thereafter transported to the desired site to be assembled in position.

In order that the said invention may be clearly understood and readily carried into effect the same will now be described more fully with reference to the accompanying drawings which show by way of example only, various typical units constructed and assembled according to the present invention and in which:—

Figure 1 is a sectional plan view and,

Figure 2 an elevation of a bungalow of standardized design and unit construction the units being constructed and assembled according to the present invention.

Figure 3 is a perspective view of an ordinary wall section adapted for use either as an outer wall section or an inner party wall section.

Figure 4 is a perspective view showing the method of connecting the floor sections to contiguous wall sections on the ground and first floors respectively.

Figure 5 is an enlarged view showing one method which may be employed for bolting together contiguous sections.

Figure 6 is a perspective view showing a portion of a foundation wall associated with make-up pieces forming a damp course and also illustrating one method of bolting together the said foundation wall and make-up pieces to the ground floor member; the lower portion of a wall member being located above the ground floor member.

Figure 7 is a sectional view showing two contiguous wall sections bolted together. In this view the inner lining is also shewn but in connection with the other standard sections the lining material for the various hollow sections has been omitted.

Figure 8 is an elevation and,

Figure 9 is an end view of a two-storied building constructed according to the present invention.

Throughout the drawings A, A indicates wall sections of standardized design and of the height of one story. B, B are window sections. C, C are door sections. E, E are partition wall sections. F, F are floor sections. G, G are fire place sections, and H, H are standard chimney tops.

These sections are typical of the method employed and have merely been selected to show by way of example, the principle of construction involved and it will be understood that the roof sections I, I as also the gable sections, gutter sections, waste pipe sections, staircases J, etc., are also of standardized design. K (Figure 6) shows part of one of the solid foundation pieces. L is part of a make-up piece forming a damp course.

F (Figures 6 and 8) shows one of the floor sections in a position where it is ready

to be connected to the make-up piece L₄ (Figure 6) or to the wall sections A, A (Figure 4). In Figure 18 the lower portion of a wall section is also shown ready to be attached to the floor section F. M, M (Figure 1) are standard corner pieces which are also of the height of the one floor or slightly larger, and N, N are intermediate junction pieces.

10 Each section is provided at its edges or ends with bosses a and recesses a' adapted to engage within corresponding bosses and recesses in contiguous or abutting sections. Bolts a² and bolt holes a³ are provided at 15 suitable points in the various sections to allow the same to be bolted together, the bolts in certain cases being embedded in the sections and projection therefrom as shown at Figure 4. As shown in Fig. 4, the wall 20 sections A are formed at their ends with a plurality of channels a, a'. The floor sections are provided with corresponding recesses and projections, and in the assembling of the building structure the several units 25 are so combined that the projections and recesses intermesh with each other and form an interlocking joint each with the other. By providing a plurality of channels, as shown, the wall section A also forms a binding 30 means on abutting floor sections by reason of the fact that each channel of the wall section overlies and intermeshes with a corresponding projection on each of two floor sections. Similarly, when the wall section 35 forms the exterior wall of the building structure, the channels intermesh with an interlock the facing strip or make-up piece L, as shown in Figs. 4 and 6. The sections may also be secured together by cement, mortar 40 or the like, and/or a weathertight lining material may be used as shown at a⁴.

Each standard hollow section comprises an outer portion a⁵ to which a separate inner lining a^{6*} is attached, each section having vertical and transverse ribs a⁶ and a⁷ formed integral with the different sections. The ribs a⁶ may be provided with openings to accommodate electric leads, gas or water pipes, etc., or the electric leads, pipes, etc., 50 may be located in place during manufacture ready to be coupled up to adjacent sections during erection. The inner lining a^{6*}, may

be partially or completely finished so far as internal mouldings, ornamentations, etc., are concerned. In the one story dwelling house 55 shown at Figures 20 and 21 the same principle of construction is involved, but in this case the ends of the floor sections are of the form shown at Figure 8 so as to accommodate the upper and lower wall, window and door sections, the material a⁸ which forms the ceiling being attached to the floor sections F, F.

It will thus be seen that a dwelling house or the like of standardized design can be constructed merely by bringing together individual units, one unit forming a standard wall section, a second containing a window, a third a door, another being a floor section, and so on. Also that by varying the relative 70 positions of the different units a very large number of arrangements, designs and shapes can be produced. As the various units are provided with ridges and projections which lock or dovetail into adjacent sections, they 75 form a structure which as a whole is rigid and durable.

What I claim and desire to secure by Letters Patent of the United States is:—

A building structure comprising walls 80 consisting of building units of concrete admixed with fibrous material, whereby the units are rendered light in weight in proportion to their size and capable of being readily handled, said units having a series 85 of ribs on one face thereof and interlocking projections on the top surface and one end surface thereof, and corresponding complementary recesses in the bottom surface and the other end surface thereof, the unit being of a length sufficient to extend vertically 90 the height of one story, a floor disposed upon said wall comprising slabs some of which have end portions substantially half the thickness of the wall units and having 95 projections upon their upper surface and recesses in their lower surfaces, said projections and recesses on the floor portions being of substantially the same size as the similar projections and recesses on the wall 100 units, whereby the floor may be interlocked with the said wall.

CHARLES DENNISTON BURNEY.
